(57) **CLAIM**

The ornamental design for a flask for perfumery product, as shown and described.

DESCRIPTION

FIG. 1 is front view of a flask for perfumery product showing my design.

FIG. 2 is rear view thereof.

FIG. 3 is a right side view thereof, the left side view being a mirror image of FIG. 3.

FIG. 4 is a top view thereof.

FIG. 5 is a bottom view thereof; and,

FIG. 6 is a perspective front, top and right side view thereof. In the drawings, the broken lines in FIG. 5 depict portions of a bottom that form no part of the claimed design.
